[57] CLAIM

The ornamental design for a reconfigurable dinosaur toy, substantially as shown and described.

DESCRIPTION

FIG. 1 is a front side perspective view of a reconfigurable dinosaur toy showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a front perspective view of the design shown in FIGS. 1 through 7 reconfigured in a battle station configuration;

FIG. 9 is a front perspective view of a modified form of the design shown in FIG. 8;

FIG. 10 is a front perspective view of the design shown in FIGS. 1 through 7 reconfigured in a satellite station configuration; and

FIG. 11 is a front perspective view of a modified form of the design shown in FIG. 10.
